UNITED STATES PATENT OFFICE.

JOHN D. RORRES, OF CHICAGO, ILLINOIS.

DESIGN FOR A CAP.

Application filed August 20, 1925. Serial No. 14,541. Term of patent 14 years.

To all whom it may concern:

Be it known that I, JOHN D. RORRES, a citizen of the United States, residing at Chicago, in the county of Cook and State of Illinois, have invented a new, original, and ornamental Design for Caps, of which the following is a specification, reference being had to the accompanying drawing, forming part thereof.

Figure 2 is a side elevation of a cap. The shading of the lower broad band, the upper smaller band, and the background of the insignia by horizontal lines is intended to indicate the color, light blue.

I claim:

The ornamental design for a cap, as shown.

JOHN D. RORRES.
